US00D808528S

(12) **United States Design Patent** (10) **Patent No.:** **US D808,528 S**
Lohrenz et al. (45) **Date of Patent:** **** Jan. 23, 2018**

(54) **HOLDER FOR A BRACHYTHERAPY DEVICE**

(71) Applicant: **SALUTARIS MEDICAL DEVICES, INC.**, Tucson, AZ (US)

(72) Inventors: **Ryan L. Lohrenz**, Vail, AZ (US); **Tianna D. Benson**, Tucson, AZ (US); **Laurence J. Marsteller**, Tucson, AZ (US); **Russell J. Hamilton**, Tucson, AZ (US)

(73) Assignee: **SALUTARIS MEDICAL DEVICES, INC.**, Tucson, AZ (US)

(**) Term: **15 Years**

(21) Appl. No.: **29/576,148**

(22) Filed: **Aug. 31, 2016**

(51) LOC (11) Cl. **24-01**

(52) U.S. Cl.

USPC **D24/158**

(58) **Field of Classification Search**

USPC D24/107, 158-161, 185, 186, 187, 231, D24/128, 133, 140, 150, 172; D8/349

CPC A61N 5/1014; A61N 5/1017; A61N 2005/101; A61N 2005/1007; A61N 2005/1009

(57) **CLAIM**

The ornamental design for a holder for a brachytherapy device, as shown and described.

DESCRIPTION

FIG. 1 is a perspective view of a holder for a brachytherapy device showing our new design;

FIG. 2 is a front view thereof;

FIG. 3 is a back view thereof;

FIG. 4 is a side view thereof, the opposite side view being a mirror image thereof;

FIG. 5 is a top view thereof; and,

FIG. 6 is a bottom view thereof.

1 Claim, 3 Drawing Sheets
